UNITED STATES PATENT OFFICE.

WELLINGTON I. CLEMENTS, OF NORFOLK, VIRGINIA.

SAILOR'S REVERSIBLE WATERPROOF FLAT CAP.

Application filed October 1, 1926. Serial No. 138,890.

This invention relates to and has for one of its objects to provide a sailor's flat cap with a lining which, when the cap is reversed or turned inside out, will fully protect it from the rain and which when disposed outermost will not detract from the appearance of the cap.

A further object of the invention is to provide a cap of this character which when reversed will provide a water-proof shield for the back of the head and neck.

With the foregoing and other objects in view, the nature of which will become apparent as the description proceeds, the invention consists of the novel construction, combination and arrangement of parts hereinafter fully described and claimed, and illustrated in the accompanying drawings, wherein:

20 Figure 1 is a sectional view taken on a plane extending vertically and centrally through a sailor's flat cap embodying my invention,

25 Figure 2 is a bottom plan view of the cap, Figure 3 is a view similar to Figure 1 of the cap reversed,

30 Figure 4 is a sectional view taken on a plane extending centrally and vertically through a slightly modified form of the cap,

35 Figure 5 is a similar view of the modified form of the cap reversed, and

Figure 6 is a view similar to Figure 5 of a further modified form of the cap.

Corresponding and like parts are referred 35 to in the following description, and designated in the several views of the accompanying drawings, by similar reference characters.

In the drawings, 1 designates the crown, 40 2 the headband, 3 the grommet, 4 the sweat band, 5 the inner ornamental flap, and 6 the ribbon of a sailor's flat cap. The flap 5 is of annular formation, is split as shown at 7 and is secured at its outer edge or periphery as shown at 8 to the headband 2 adjacent the upper end of the latter. Normally the flap 5 occupies the substantially horizontal position shown in Figure 1 and the distance between its inner and outer peripheries is 45 greater than the vertical dimension of the head band 2.

In accordance with my invention, the circular top 1^a of the crown 1 is provided with a circular lining 9 of water-proof material, the annular bottom 1^b of the crown 55 is provided with an annular lining 10 of

water-proof material, and the flap 5 is provided at its top side with an annular lining 11 of water-proof material. The periphery of the lining 9 and the outer periphery of the lining 10 are connected to the periphery of the crown 1, as shown at 12, and the inner periphery of the lining 10 and the outer periphery of the lining 11 are connected at the upper end of the 60 headband 2 as shown at 13. The linings 9, 10 and 11 are adapted when the cap is reversed to fully protect it from the rain. When the cap is in this or its reversed condition, the lining 9 extends across the outer side of the top 1^a of the crown 1, the lining 10 extends across the outer side of the bottom 1^b of the crown, and the adjacent and united portions of these linings extend over the periphery of the crown. Also, when 70 the cap is in this condition, the flap 5 extends downwardly over the sweat band 4, which is usually made of fine material, and the lining 11 is located at the outer side of the flap. The flap 5 and lining 11 extend 75 below the lower edge of the headband 2, and in view thereof the sweat band 4 is fully protected from the rain. To reverse the cap, it is only necessary to first remove the grommet 3, and after the cap has been reversed, the grommet is replaced in the crown 1.

As shown in Figures 4 and 5, the crown 1 may be provided with but one lining of water-proof material which is designated 9^a and extends over the top and edge of the 80 crown. In these figures, it is also shown that the water-proof lining 11^a for the flap 5^a may be extended to provide, when the cap is reversed, a shield 14 for the back of the head and neck. The front edges 15 of the shield 14 are of arcuate formation so as to prevent the shield from covering the ears and thus interfering with the hearing of the sailor. The shield 14 is adapted to be secured tightly about the neck by straps 16. 95 In order that it may present a neat appearance when folded within the cap as in Figure 4, the shield 14 is provided with a lining 17 which may be made separately from or integrally with the flap 5^a.

As shown in Figure 6, the flap and shield may be made separately and detachably connected together. In this figure 5^b, designates the flap, 11^b the water-proof lining for the flap, and 14^b the shield. The shield 14^b is detachably connected to the flap 5^b by any suitable elements such as the stud and 110

socket fastenings 18. This shield is also provided with a lining 17^a so that it will when folded within the cap present a neat and attractive appearance.

- 5 From the foregoing description, taken in connection with the accompanying drawings, it should be apparent that I have provided a sailor's flat cap which when reversed will fully protect the crown and sweat band from 10 the rain. Furthermore, the cap will when reversed, provide a shield adapted to fully protect the back of the head and neck from the rain. It should be understood that the drawings are merely illustrative and do not pretend to give exact proportions. Furthermore, the said drawings are illustrative of a preferred construction, it being my expectation that various changes and modifications may be made without departing from 15 the spirit and scope of my invention.

What is claimed is:—

1. A reversible cap comprising a crown having a circular top and an annular bottom, the bottom underlying the top and connected at its outer periphery to the periphery of the top, a head band connected at its upper edge to the inner periphery of the bottom, an annular flap connected at its outer periphery to the upper edge of the 20 head band, the flap normally occupying a substantially horizontal position within the cap and adapted to extend downwardly over the outer side of the head band when the cap is reversed, a circular lining of water- 25 proof material extending across the inner side of the top and secured at its periphery to the periphery of the crown, said lining being adapted to extend across the outer side of the top when the cap is reversed, and 30 an annular lining secured to the flap and extending across the upper side thereof, and said last named lining being adapted to extend over the outer side of the flap when the cap is reversed.
- 45 2. A reversible cap comprising a crown having a circular top and an annular bottom, the bottom underlying the top and connected at its outer periphery to the periphery of the top, a head band connected at its upper edge to the inner periphery of the bottom, an annular flap connected at its outer 35 periphery to the upper edge of the head band, said flap normally occupying a substantially horizontal position within the cap and adapted to extend downwardly over the outer side of the head band when the cap is reversed, the distance between the inner and outer peripheries of said flap being greater than the vertical dimension of the 40 head band, a circular lining of water-proof material extending across the inner side of the top, an annular lining of water-proof material extending across the inner side of the bottom, and an annular lining of water- 45 proof material extending across the upper side of the flap, the adjacent peripheries of 50 said linings being secured together and to the cap and said linings being adapted to occupy positions externally of the cap when the cap is reversed.
- 55 3. A reversible cap comprising a crown having a circular top and an annular bottom, the bottom underlying the top and connected at its outer periphery to the periphery of the top, a head band connected at its upper edge to the inner periphery of the bottom, an annular flap connected at its outer periphery to the upper edge of the head band, said flap normally occupying a substantially horizontal position within the 60 cap and adapted to extend downwardly over the outer side of the head band when the cap is reversed, a circular lining of water-proof material extending across the inner side of the top, an annular lining of water-proof material extending across the inner side of the bottom, and an annular lining of water- 65 proof material extending across the upper side of the flap, said linings having their adjacent peripheries connected together and to the cap and adapted to occupy positions at the outer side of the cap when the cap is reversed.

annular lining secured to the flap and extending across the upper side thereof, and said last named lining being adapted to extend across the outer side of the flap when the cap is reversed.

3. A reversible cap comprising a crown having a circular top and an annular bottom, the bottom underlying the top and connected at its outer periphery to the periphery of the top, a head band connected at its upper edge to the inner periphery of the bottom, an annular flap connected at its outer periphery to the upper edge of the head band, said flap normally occupying a substantially horizontal position within the cap and adapted to extend downwardly over the outer side of the head band when the cap is reversed, a circular lining of water-proof material extending across the inner side of the top, an annular lining of water-proof material extending across the inner side of the bottom, and an annular lining of water- 90 proof material extending across the upper side of the flap, said linings having their adjacent peripheries connected together and to the cap and adapted to occupy positions at the outer side of the cap when the cap is reversed.

4. A reversible cap comprising a crown having a circular top and an annular bottom, the bottom underlying the top and connected at its outer periphery to the periphery of the top, a head band connected at its upper edge to the inner periphery of the bottom, an annular flap connected at its outer periphery to the upper edge of the head band, said flap normally occupying a substantially horizontal position within the cap and adapted to extend downwardly over the outer side of the head band when the cap is reversed, the distance between the inner and outer peripheries of said flap being greater than the vertical dimension of the head band, a circular lining of water-proof material extending across the inner side of the top, an annular lining of water-proof material extending across the inner side of the bottom, and an annular lining of water- 100 proof material extending across the upper side of the flap, the adjacent peripheries of said linings being secured together and to the cap and said linings being adapted to occupy positions externally of the cap when the cap is reversed.

5. A reversible cap comprising a crown having a circular top and an annular bottom, the bottom underlying the top and connected at its outer periphery to the periphery of the top, a head band connected at its upper edge to the inner periphery of the bottom, an annular flap connected at its outer periphery to the upper edge of the head band, a flap normally occupying a substantially horizontal position within the cap and adapted to extend down-

wardly over the outer side of the head band when the cap is reversed, a circular lining of water-proof material extending across the inner side of the top and secured at its periphery to the periphery of the crown, said lining being adapted to extend across the outer side of the top when the cap is reversed, and an annular lining secured to the flap and extending across the

upper side thereof, and said last named lining being adapted to extend over the outer side of the flap when the cap is reversed, and the lining for the flap extends beyond the lower edge thereof when the cap is reversed to provide a head and neck shield. 10 15

In testimony whereof I affix my signature.

WELLINGTON I. CLEMENTS.
